NOTEBOOK

Volney E. Larsen, Chicago, Ill., assignor to White
& Wyckoff Mfg. Company, Holyoke, Mass., a
corporation of Massachusetts

Application August 29, 1936, Serial No. 98,505

4 Claims. (Cl. 281—33)

This invention relates to improvements in books and is directed more particularly to the provision of an improved notebook which may be readily set up and retained in an upright reading position.

5 It is one of the principal objects of the invention to provide a notebook or the like having what may be called a non-skid surface so that the notebook may be safely supported in an upright reading position without sliding along a desk top or the like. As a special feature, according to this invention, the book includes a pair of relatively stiff cover members one of which at least has a non-skid or friction member associated therewith and the arrangement is such that the covers of the book may constitute an easel for supporting the book in an upright position and the non-skid member prevents the edges of the covers sliding along the desk top so that the easel-like support does not collapse.

20 The book of this invention includes hinged-together cover members which are readily swingable relative to one another and to the leaves of the book. The construction is simple in form so as to be easy and economical to manufacture.

25 Various other novel features and advantages of the invention will become more apparent after a reading of the following description, reference being had to the accompanying drawing wherein:

Fig. 1 is a plan view of the book of the invention;

Fig. 2 is a side elevational view of the book in set-up position; and

Fig. 3 is a partial side elevational view of one of the covers of the book showing the non-skid member associated therewith.

Referring now to the drawing more in detail, the invention will be fully described.

The book of the invention includes a stack of leaves 2 and a pair of relatively stiff cover members 4 and 6. The cover members 4 and 6 are of course normally disposed on opposite sides of the stack 2 and they are hinged together for swinging movements by means of some suitable binding means B.

45 In the form shown, the binding B consists of a spiral member, such as is shown in United States Letters Patent No. 1,516,932 of November 25, 1934 to Staab, and is received in suitably aligned and spaced openings provided in the leaves and covers. 50 It is to be understood, however, that the particular manner in which the leaves and covers are connected may be varied as desired.

It is usual to form the covers of notebooks of some stiffish material, such as cardboard or the

like, and they are commonly rectangular in shape as shown. In this way, the covers may be arranged so that they are disposed in the form of an inverted V with their lower marginal edges resting on a surface S, all as shown in Fig. 2.

5 In this upright position, it will be seen the leaves 2 are supported in an inclined position and the reading matter on the leaves is more readily visible. This inverted V or upright position is not readily maintained, however, and very often 10 the book collapses. The disadvantages of this are obvious and it is to overcome them that the invention is directed.

Accordingly, I provide the book with a non-skid surface which is adapted to engage the surface S and prevent the edges of the covers 4 and 6 from sliding. As will appear, either or both of the cover members may have this non-skid surface.

One or both of the cover members 4 and 6 is 20 provided with one or more seats and these preferably take the form of slots 8 which extend inwardly from a marginal side edge thereof as shown. Preferably the slots 8 are disposed in substantial parallelism with the lower marginal edges of the covers although the particular form of the slots may be varied.

25 Then a band 10 of friction non-skid material is provided and it is arranged to have a part disposed in one of the seats and another part embracing the lower marginal edge of the cover, 4 or 6, with which it is associated. This member 10 may take the form of an endless rubber band which extends into the slot 8 and extends around the part of the cover which lies between the slot and the lower marginal edge of the cover, all as shown.

30 It is obvious that one or more bands may be associated with each side of the covers, although I have found that the non-skid surface provided by a single band satisfactorily prevents collapsing of the book. It will be seen that while in the position shown in Fig. 2, the covers form an easel and, with the friction member extending around a free edge of the cover and through the seat spaced from that edge, the easel-forming position is easily maintained.

35 The seats may take various forms as may be desired such as open-ended slots of various shapes or openings and there may be one or more endless bands associated with each seat. Or, if desired, there may be more than one seat and the band or bands need not be endless. In carrying out the invention it is desired that an anti-skid member 45

50

55

or members be associated with the cover or covers by passing over or around the edge of the cover and held thereon by means of a seat or seats which receive the said member.

- 5 While I have described the invention in great detail and with respect to a preferred form thereof in connection with notebooks, it is not desired to be limited thereto since the invention is adapted for use in connection with all kinds of
10 books and since many changes and modifications may be made therein without departing from the spirit and scope of the invention. What it is desired to claim and secure by Letters Patent of the United States is:
- 15 1. The combination of a book having covers and hinge connections with anti-skid means therefor when the edges of the covers of the book are set on a support comprising, an endless band of friction material embracing an edge of one of
20 the covers remote from the hinge connections and seated in a seat provided in said one cover.
2. The combination of a book having covers and hinge connections at their upper edges with anti-skid means therefor when the lower edges of
25 the covers of the book are set on a support comprising, an endless band of friction material extending around the part of the cover which lies between the lower marginal edge of one of the covers and a slot provided in said cover at a
30 distance from said lower edge.

3. As a new article of manufacture, a notebook comprising a stack of leaves, a cover member disposed adjacent one side of the stack, a second cover member disposed adjacent the other side of the stack, binding means associated with adjacent marginal edge portions of said stack and cover members which permits the covers to be moved into adjacency, one of said cover members being provided with an open-ended slot at a distance from said binding means, and a friction member embracing that marginal edge of said one cover member which is opposite the binding means and extending through said slot.

4. As a new article of manufacture, a notebook comprising a stack of leaves, a cover member disposed adjacent one side of the stack, a second cover member disposed adjacent the other side of the stack, binding means associated with the upper marginal edge portions of said stack and cover members which permits the covers to be moved into adjacency, one of said cover members being provided with an open-ended slot at a distance from said binding means, and an endless band of friction material embracing that part of said one cover member which is disposed between said slot and the lower marginal edge of the cover member.
